(57) **CLAIM**

The ornamental design for a frame member for a door assembly, as shown and described.

DESCRIPTION

FIG. 1 is a front perspective view of a frame member for a door assembly, according to the invention;

FIG. 2 is a front view of the frame member for a door assembly of FIG. 1;

FIG. 3 is a left side view of the frame member for a door assembly of FIG. 1, with the right side view being a mirror image thereof;

FIG. 4 is a top view of the frame member for a door assembly of FIG. 1;

FIG. 5 is a bottom view of the frame member for a door assembly of FIG. 1;

FIG. 6 is a perspective detail view taken from the encircled area indicated by the reference number 6 at the top left corner of the frame member for a door assembly of FIG. 1, which has been enlarged to better show the contours of the frame;

FIG. 7 is a front view of the frame member for a door assembly, including section lines 8-8 and 9-9 at horizontal and vertical portions of the frame member, respectively;

FIG. 8 is a sectional view of the frame member for a door assembly of FIG. 1, taken along section line 8-8 of FIG. 7; and,

FIG. 9 is a sectional view of the frame member for a door assembly of FIG. 1, taken along section line 9-9 of FIG. 7. The broken line portions of the drawings depict portions of the frame member for a door assembly that form no part of the claimed design.

The dash-dot-dot-dash broken lines in FIGS. 1 & 6 depict the limits of the enlarged view and form no part of the claimed design.
